CLAIM

The ornamental design for a detergent input for washing machine, as shown and described.

DESCRIPTION

FIG. 1 is a front perspective view of the detergent input for washing machine showing our new design; FIG. 2 is a front view thereof; FIG. 3 is a back view thereof; FIG. 4 is a left side view thereof; FIG. 5 is a right side view thereof; FIG. 6 is a top plan view thereof; FIG. 7 is a bottom plan view thereof; and, FIG. 8 is a reference view showing the state of use that the claimed design has been attached to the washing machine. The broken lines depict portions of the detergent input for washing machine that form no part of the claimed design. The portions of FIG. 8 drawn in broken lines show environmental structure only and form no part of the claimed design.
